UNITED STATES PATENT OFFICE.

JULIAN S. JACOBS, OF SPRINGFIELD, VERMONT, ASSIGNEE TO JOHN T. SLACK CORPORATION, OF SPRINGFIELD, VERMONT, A CORPORATION OF VERMONT.

RAG-STOCK FEEDER.

1,381,878.

Specification of Letters Patent. Patented June 14, 1921.

Application filed October 20, 1919. Serial No. 322,053.

To all whom it may concern:

Be it known that I, JULIAN S. JACOBS, a citizen of the United States, and resident of Springfield, in the county of Windsor and 5 State of Vermont, have invented certain new and useful Improvements in Rag-Stock Feeders, of which the following is a specification.

This invention relates to rag feeding machines of the type disclosed in Letters Patent of the U. S. No. 1,258,222 dated March 10, 1918, or any type of feed apparatus for feeding rag-stock, wool or other similar material to a picker or other machine by 15 which the material is to be treated.

Heretofore it has been customary to use a comb for straightening out, opening or leveling the rag-stock or other material that is being carried up on the feed apron to be 20 delivered to the working machine, but such combs have been made in the form of a saw tooth or similar to the blade of a mowing machine thus presenting a series of V-shaped flat teeth extending in a single plane 25 nearly parallel to the plane of the feed apron or conveyer. Combs of this type do not perform the opening and leveling operation in a very efficient or satisfactory manner, and it is the object of the present invention to provide a comb for this purpose which while being simple in construction 30 shall be more effective in opening lumps or bunches of material and laying the material substantially parallel to the travel of the 35 apron so as to produce a more uniform feed or delivery of the material or rag-stock to the operating machine.

To this end the invention comprises the combination with a feed apron or conveyer 40 of a comb embracing substantially a longitudinal supporting member and a series of thin blades set edgewise transversely of the supporting member at suitable intervals apart in parallelism with each other so that 45 their thin edges may engage the approaching rag-stock carried by the spikes of the apron and properly distribute and level the rag-stock on the conveyer to secure a substantial uniform delivery of the material.

50 This and other features of the invention will be set forth in this specification and will be defined in the claims annexed hereto.

In the accompanying drawing I have 55 illustrated a simple and convenient construction embodying the principles of this

invention, so much of the feeding device or conveyer being shown as is necessary to an understanding of the present invention.

In the drawings—

Figure 1 is a perspective view showing the operation of the conveyer and related parts in combination with the distributing or leveling comb.

Fig. 2 is a vertical cross section through the comb showing a method of fastening the blades to the supporting bar.

Fig. 3 is a front view showing two adjacent blades secured to the supporting member.

The type of the feed apparatus shown in the drawings is similar in construction to that shown in our above-mentioned patent. In this case there is shown an assembled portion of the feed apron or slatted conveyer *a* with a part of the supporting frame work *a'* and the projecting spike bars *a*⁵ which engage the rags, wool or other substance which may be referred to under the general term "rag-stock". On the supporting brackets *b* of the frame is mounted a rock-shaft *b'* which is oscillated through a small arc by means of the crank *b*² connected with the pitman *b*³ so as to produce an oscillation of the comb toward and away from the spiked conveyer on whose points are impaled or caught the rag-stock which is being fed to the operating machine.

The comb itself comprising a supporting member *c* in this case shown has a longitudinal angle bar extending across the feed apron.

At suitable distances apart along the supporting bar *c*, forming the back or frame of the comb, are formed transverse slots in which are inserted thin flat blades which are set edgewise transversely of the supporting member so as to present their thin edges to the approaching rag-stock.

As best shown in Fig. 2 the blades are shaped to a downwardly projecting point 100 and have their front edges *c*³ somewhat sharpened and also preferably slightly concaved so as to cut or tear the material when it is bunched too tightly to be easily opened without such cutting action.

The blades *c'* may be secured to the supporting member *c* in any suitable manner. However, in the drawings we have shown the upper portion of the blade bent laterally to form an ear or flange *c*² through which a 110

fastening bolt or screw may be passed to secure it to the supporting bar. With this arrangement also the slots c^{10} form an additional support for firmly holding the blades 5 edgewise to the work and maintaining them in proper operative position.

The comb is adjustably mounted in operative position by means of vertical carrying rods d which are adjustably secured in 10 brackets d' fastened to the rock-shaft b' and are set so that their sharpened hook-like points will extend to the level or even slightly below the level of the sub-adjacent row of spikes a^5 when the comb is in the 15 lowermost position of its oscillation.

With a comb having this construction it will be found that the rag-stock will be combed out, straightened and opened up so as to present a far more uniform feed of the 20 material than with the old style of combs previously used. The edgewise arrangement of the blades to the stock not only permits the cutting through of tightly wadded lumps of material but the arrangement of 25 the blades more effectively secures a straightening out of the material in lines substantially parallel with the direction of the feed.

What we claim is:

30 1. In a machine for feeding rag-stock or the like, the combination of a traveling feed apron provided with a series of projecting spikes for engaging the rag-stock and conveying it to the delivery end of the machine, 35 a coöperating distributing comb comprising a cross-bar supported above the spiked apron and having a series of depending blades set in parallelism edgewise to the feed of the apron and secured to said cross- 40 bar at spaced intervals so as to oppose their edges against the traveling rag-stock engaged by the spikes in order to distribute the rag-stock evenly as the apron passes beneath, substantially as described.

45 2. In a machine for feeding rag-stock or the like, the combination of a spiked feed apron arranged to feed the stock to the delivery end of the machine, an oscillatory distributing comb supported in proximity to 50 said apron and comprising a transverse blade-supporting bar, and a series of blades secured at spaced intervals thereto in parallel relationship edgewise to the advancing stock whereby the thin edges of the blade 55 engage the rag-stock held by the spikes and lay it in parallelism lengthwise of the apron, substantially as described.

60 3. A comb for a rag-stock feeding machine embracing in its construction a trans- 65 verse blade-supporting bar, a series of

spaced blades secured thereto with their blades extending edgewise in parallel planes with the travel of the apron, and means for supporting said comb from an oscillatory shaft whereby the blades may be moved 65 edgewise to and fro against the rag-stock carried by the apron and lay it in parallelism lengthwise of the apron, substantially as described.

4. A comb for distributing rag-stock or 70 the like over the apron of a rag-stock feeding machine embracing a transverse blade-bar, a series of flat thin edge blades secured directly to said bar in position to present thin cutting edges to the approaching rag- 75 stock, and means for suspending said bar to permit oscillation of the comb in proximity to the surface of the apron, substantially as described.

5. A comb for a rag-stock feeder embrac- 80 ing in its construction a longitudinal sup- 85 porting member provided with a series of properly spaced transverse slots, a series of thin blades inserted in said slots to lie in parallelism with each other and secured to 85 said supporting member, substantially as de- 90 scribed.

6. A comb for a rag-stock feeder embrac- 90 ing in its construction a longitudinal angle 95 bar provided with transverse slots, a series of teeth inserted in said slots and comprising thin parallel blades each formed with a laterally extending lug and affording means for bolting the tooth securely to said angle bar.

7. A comb for a rag-stock feeder embrac- 100 ing in its construction a lateral supporting member, a series of thin blades formed with laterally projecting ears and fastening means passed through said ears to secure the individual blades firmly to said supporting member in parallelism with each other transversely of the supporting member, sub- 105 stantially as described.

8. A distributing comb for a rag-stock 110 feeding machine embracing in its construc- 115 tion a blade-supporting bar adapted to be mounted in juxtaposition to the apron of the feeder, a series of thin blades set edge- wise transversely of said blade-bar so as to lie in parallelism with the travel of the apron and rigidly secured to said blade-bar, the forward edges of said blades being sharpened and curved to tear apart and cut approaching bunches of rags, substantially as described.

In witness whereof, I have subscribed the above specification.

JULIAN S. JACOBS.
